YARN PACKAGE TESTING APPARATUS

Noel J. Folsom, Narrows, Va., assignor to Celanese Corporation of America, a corporation of Delaware

Application March 21, 1946, Serial No. 656,109

7 Claims. (Cl. 73—81)

1

This invention relates to a testing apparatus and relates more particularly to an improved testing apparatus adapted for determining the density or firmness of the windings on yarn packages such as cones, bobbins, cheeses and the like.

Yarns which are sold to mills where they are knitted or woven into fabrics are usually shipped in the form of packages of various shapes such as, for example, cones, bobbins or cheeses. In order to be utilized most efficiently, not only must each of the several types of yarn packages be of standard weight and dimensions but, in addition, the density or firmness of the yarn windings constituting the yarn package must also be substantially uniform. Loosely wound yarn packages and loosely wound cones or cheeses in particular are difficult to handle since the edges are soft, allowing some of the yarn windings to slough off. The resulting tangle causes a considerable waste of yarn since the yarn package must be unwound until the tangled yarn is removed. The unwound yarn is usually discarded. Yarn packages which are wound too tightly put an excessive strain in the yarns which is a frequent cause of broken filaments, particularly where the yarns forming the package are only of a comparatively low twist.

These difficulties make necessary some form of testing device whereby the density and firmness of the yarn packages formed may be determined, thus indicating whether the winding machines producing said packages are operating properly. Heretofore, the density and firmness of a yarn package was determined by driving a pointed rod into the windings of the yarn package by means of a tensioned spring or by means of compressed air acting on a piston to which said pointed rod is suitably connected. In order for said penetrating test device to yield uniformly reliable results, not only must the force driving said pin be uniform but the position of the testing device with respect to the yarn packages undergoing density tests must not vary from the position during preceding tests. Any variation in the angle at which the penetrating pin strikes the yarn windings will produce readings which will vary from package to package even though the individual firmness and density of the several packages tested may be substantially uniform.

It is, therefore, an important object of this invention to provide an improved testing frame or jig adapted to be employed in connection with the testing of yarn packages whereby the device employed for making the desired tests will be

2

accurately and uniformly placed at all times with respect to the yarn package being tested.

Another object of this invention is the provision of a testing frame or jig which is adjustable and adapted to accommodate different forms and sizes of yarn packages undergoing firmness and density tests.

Other objects of this invention will appear from the following detailed description and the accompanying drawing.

In the drawing,

Fig. 1 is a view, in perspective, of my improved testing frame or jig, including a yarn package holder, having a pneumatically driven testing device mounted thereon.

Fig. 2 is a perspective view of a support employed in connection with said jig and adapted to hold a spool of yarn for testing, and

Fig. 3 is a perspective view of a modified yarn package support holder on which yarn packages such as cheeses may be mounted.

Like reference numerals indicate like parts throughout the several views of the drawing.

Referring now to the drawing, and more particularly to Fig. 1, the novel frame or jig of my invention, generally indicated by reference numeral 4, comprises a bed plate 5 and a back plate 6 which are held together by a pair of brackets 7 attached to each of said plates by bolts 8. Pivotally mounted on a pin 9 set in a shackle 10 attached to bed plate 5 is a substantially rectangular support member 11 provided on a portion of one end thereof with a semi-circular groove 12, said end also having a threaded rod 13 set therein. Adapted to rest in the groove 12 is a circular rod 14 the opposite end of which is threaded into back plate 6 and held in fixed position in said plate 6 by means of a lock nut 15.

Rod 14 carries a yarn package support holder 16, shown having a conical yarn package 16' thereon, formed of wood, metal or other suitable material provided at one end with slots 17 which are so situated as to impart an appreciable degree of flexibility to the several integral fingers 18 thus formed. Fingers 18 may be expanded through the action of a conically shaped expander 19 slidably mounted on rod 14. Expander 19 may be forced into the slotted end of yarn package support holder 16 by the action of 50 a lever 20 which is pivotally mounted on a pin 21 carried by a bracket 22 mounted on bed plate 5.

The testing device employed for determining the firmness and density of the yarn packages through the penetrating action of a pointed rod is of a standard design well known in the art and

is generally indicated by reference numeral 23. The testing device 23 is actuated by means of air under pressure which is led into a cylinder 24 through a conduit 25, the compressed air acting on a piston (not shown) enclosed therein which cooperates with a piston rod 26 extending downwardly from cylinder 24. Rod 26 is threaded into a sleeve 27 which also has a rod 28 threaded therein leading into and operating the pointed rod 28' of said testing device 23 when rod 28 is forced downward by the air-driven stroke of the piston.

The assembly comprising testing device 23 and air cylinder 24 is mounted on a unitary bracket assembly generally indicated by reference numeral 29. Bracket 29 comprises arms 30 and 31 which are attached to cylinder 24 by means of bolts 32 and 33, respectively. Arm 30 is attached to a block 34 by a bolt 35 and the lower end of arm 31 is attached to a block 36 by another bolt (not shown). Blocks 34 and 36 are braced by parallel cross-bars 37, only one of which is shown. Blocks 34 and 36 are slidably mounted on a pair of parallel guide rods 38 and 39 so that the entire testing assembly may be shifted along said rods to any desired horizontal position. Rods 38 and 39 are each supported at one end by a member 40 provided with arms 41 and 42, the opposite end of said rods being maintained in a bracket 43, which, in cooperation with a U-shaped member 44 and a pin 45 forms a hinge assembly generally indicated by reference numeral 46. Member 40 carrying guide rods 38 and 39 is vertically adjustable by means of knurled nuts 47 and 48 which are threaded on to rod 13.

Hinge assembly 46 may be vertically adjusted along slots 49 by means of a lock nut 50 which screws on to a threaded pin 51 integral with U-shaped member 44 and bears on a plate 52 slidably mounted between guide bars 53 and 54 attached to back plate 6 by screws 55. To avoid any lateral or rotational movement of hinge assembly 46, guide pins 56 and 57 are also provided which engage vertical slots 58 and 59 in back plate 6 as well as holes 60 and 61 in plate 52.

In order to test the firmness and density of a yarn package such as, for example, a cone wound on a tapered yarn support, knurled nut 48 is disengaged and the entire assembly comprising bracket 29, and rods 38 and 39 are pivoted upwardly about hinge assembly 46 so that they assume a vertical position. The test assembly comprising bracket 29 and bars 34 and 36 is then dropped along rods 38 and 39 until the hole 62 in arm 31 engages pin 63 set in the upper surface of back plate 6. After support member 11 is rotated about pin 9 to the horizontal position shown in dot-dash line in Fig. 1, a cone of yarn 16' is slid on to yarn package support holder 16. Member 11 is raised to a vertical position, rod 14 is set in groove 12 and lever 20 is then rotated in a suitable direction so that expander 19 is forced into the end of said yarn holder 16 spreading fingers 18, thus holding the yarn package firmly and in a fixed position. Hole 62 in bracket 29 is then disengaged from pin 63 and the entire assembly pivoted on pin 45 until arms 41 and 42 rest on knurled nut 47. Rods 38 and 39 are then adjusted so that they are parallel to the longitudinal surface of the yarn package directly under the testing device. This is effected by adjusting knurled nut 47 and knurled nut 48 as well as by sliding plate 52, upwardly or downwardly, as the case may be. When the desired parallel adjustment is made, lock nut 50 is then brought up

tightly against back plate 52 and nut 48 is tightened on arms 41 and 42.

The firmness and density of the windings of the yarn package directly under the testing device is then determined by allowing air under pressure to enter the cylinder 24. The air under pressure forces piston rod 26 and rod 28 down thereby actuating the test pin 28' and causing the latter to penetrate the yarn windings. The relative firmness and density of the yarn package is shown by the deflection of indicator 64 on a scale 65. To obtain different readings for different portions of the yarn package along a given axis thereof, the testing assembly is shifted to the desired position along rods 38 and 39. Readings for different portions of the periphery of the yarn package may be obtained by forcing lever 20 over to release expander 19 and rotating the yarn package about holder 16, thus presenting another part of periphery of the yarn package to the pin.

To test the firmness and density of yarn packages comprising bobbins, rod 14 and yarn package support 16 are removed and, as shown in Fig. 2, a rod 66 is set in posts 67 at right angles to the usual position of rod 14. A bobbin of yarn is slid on the rod 66 and the test carried out as described above after placing the test device assembly over the portion of the bobbin to be tested and adjusting rods 38 and 39 so that they are parallel to the yarn windings. In the case of cheeses wound on a yarn package support having a straight bore, a collar 68 is slid upon yarn package support holder 16 to provide the proper amount for the yarn package and the test is carried out as previously described.

It is to be understood that the foregoing detailed description is given merely by way of illustration and that many variations may be made therein without departing from the spirit of my invention.

Having described my invention what I desire to secure by Letters Patent is:

1. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of a support for said testing means, means for moving said support and said testing means through a vertical arc, means for maintaining said testing means in a predetermined position, said support means comprising guide rods on which said testing means is slidably mounted for lateral movement, and means for mounting a yarn package to be tested in a fixed position relative to the position of said testing means.

2. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, and means cooperating with said guide rods for varying the angle and elevation thereof, and a separate support for mounting a

yarn package to be tested in a fixed position relative to and beneath the position of said testing means.

3. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, means cooperating with said guide rods for varying the angle and elevation thereof comprising a vertically adjustable hinged bracket in which said guide rods are mounted at one end and a vertically adjustable rigid bracket carrying the other end of said rods, and a separate support for mounting a yarn package to be tested in a fixed position relative to and beneath the position of said testing means.

4. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, means for supporting said guide rods at a plurality of points, means for mounting a yarn package to be tested in a fixed position relative to the position of said testing means, said yarn package mounting means comprising a horizontal rod, a shaped holder carried thereby and adapted to receive a yarn package, locking means cooperating with said shaped yarn holder for locking the yarn package thereon and means including one of the supports for said guide rods for supporting said horizontal rod.

5. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, means for supporting said guide rods at a plurality of points, means cooperating with said guide rods for varying the angle and elevation thereof, and a separate support for mounting a yarn package to be tested in a fixed position relative to and beneath the position of said testing means, said support comprising a horizontal rod, a shaped holder carried thereby and adapted to receive a yarn package, locking means cooperating with said shaped yarn holder for locking the yarn package thereon and means including one of the supports for said guide rods for supporting said horizontal rod.

6. In a yarn package testing device for deter-

mining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, means for supporting said guide rods at a plurality of points, means cooperating with said guide rods for varying the angle and elevation thereof comprising a vertically adjustable hinged bracket in which said guide rods are mounted at one end and a vertically adjustable rigid bracket carrying the other end of said rods, and a separate support for mounting a yarn package to be tested in a fixed position relative to and beneath the position of said testing means, said support comprising a horizontal rod, a shaped holder carried thereby and adapted to receive a yarn package, locking means cooperating with said shaped yarn holder for locking the yarn package thereon and means including one of the supports for said guide rods for supporting said horizontal rod.

7. In a yarn package testing device for determining the firmness and density of yarn windings on a yarn package support, the combination with testing means, including a force-driven pointed testing rod for penetrating said windings and a measuring device having a scale indicating the degree of penetration of the testing rod into the yarn windings on the yarn package, of adjustable support means for maintaining said testing means in a predetermined position, said support means comprising guide rods on which said testing means is slidably mounted for lateral movement, means for supporting said guide rods at a plurality of points, means cooperating with said guide rods for varying the angle and elevation thereof comprising a vertically adjustable hinged bracket in which said guide rods are mounted at one end and a vertically adjustable rigid bracket carrying the other end of said rods, and a separate support for mounting a yarn package to be tested in a fixed position relative to and beneath the position of said testing means, said support comprising a horizontal rod, a shaped holder expandable at one end carried thereby and adapted to receive a yarn package, and lever means for expanding said shaped yarn package holder and locking the yarn package in fixed position thereon and means including one of the supports for said guide rods for supporting said horizontal rod.
